FLOATING TRAILER

Roger H. Kendall and Maynard Jordan Nathason,
Los Angeles County, Calif.

Application August 9, 1955, Serial No. 37,397

Term of patent 14 years

(Cl. D71—1)

Fig. 1 is a perspective view of a floating trailer embodying our new design showing one side, the top and the front thereof.

Fig. 2 is an elevational view of the side opposite that shown in Fig. 1.

Fig. 3 is rear end view of the floating trailer.

We claim:

The ornamental design for a floating trailer, as shown.
